UNITED STATES PATENT OFFICE.

HENRY J. LUFF, OF CLEVELAND, OHIO, ASSIGNOR TO FRUIN & WALKER COMPANY, OF CHICAGO, ILLINOIS, A CORPORATION OF ILLINOIS.

PLUMBING SYSTEM.

Application filed December 4, 1924, Serial No. 753,808. Renewed May 3, 1927.

Fig. 1 is an elevation of a system embodying my improvements; Fig. 2 is a section on line II—II of Fig. 1 showing the waste connections; Fig. 3 is a partial vertical section 5 of the combined vent and waste stacks; Fig. 4 is a section on line IV—IV of Fig. 3; Fig. 5 is a section on line V—V of Fig. 4; Figs. 6 and 7 are sections on lines VI—VI and VII—VII of Fig. 3; Figs. 8 and 9 are modified forms of top floor fittings; and Fig. 10 is a section of a modified form of a lower floor fitting.

My invention relates to new and useful improvements in plumbing systems and in 15 fittings therefor. The object of my invention is to provide fittings to be used to connect a vertical soil or waste pipe to a vent pipe of substantially the same diameter and to a series of lateral soil and waste 20 branches leading from water closets, bath tubs, wash basins, or similar fixtures, which will effectually prevent the siphonage of the seals of the fixture traps at the end of said lateral branches, prevent back air pressure 25 from disturbing the seals of said fixture traps, and maintain an efficient air circulation throughout the entire system. My invention also provides in the event that a stoppage occurs in said vertical soil or waste 30 pipe the connection between the vertical waste and vent pipes will permit waste from fixtures at a higher level to pass into and down the vent pipe and will thus prevent the fixtures immediately above the point of 35 stoppage from overflowing. The connections between the waste and vent pipe are, however, arranged at such a level as to permit the waste to stand in one or more of the fixtures so as to indicate a stoppage.

40 My invention is designed to reduce to a minimum the length of the lateral branches and the number of vent pipes now found necessary to prevent the siphonage of the seals of the fixture traps, and to prevent 45 back air pressure from disturbing the seals of said fixture traps.

My invention also comprises the various features hereinafter described and claimed.

50 Referring to the drawings, in which I have shown my invention applied to a twin stack system employing composite fittings which form parts of both the waste and vent stacks, 2 indicates a fitting formed to merge the lower ends of the waste and vent 55 stacks and having at its upper end hubs 3

and 4 arranged for reception of the lower ends of the combination fitting 5, which has the waste and vent portions 6 and 7, respectively. At a distance above the bottom of the portion 6 are openings 8 for the fixture 60 wastes which enter an enlarged portion 9 of the portion 6, which enlargement extends upwardly to the upper end of the fitting and is connected by a crossover 10 or opening with the vent portion 7 at a distance sufficiently above the waste openings 8 so that if the stack is clogged immediately below the waste openings 8 the waste will back up in the lateral branches 8^a and stand in one or more of the fixtures, such as the bath tub 70 A, closet B or other fixtures connected at this point, so that it will indicate a stoppage. The cross section of the enlarged portion 9 of the fitting 5 is such as to be equal to the combined normal cross sectional area of the 75 waste stack and of the vent pipe. I have also indicated an opening 11 near the top of the waste portion 6 of the fitting 5 for connection with a sink or laundry tub.

Seating in the hubs of the fitting 5 is the 80 fitting 12, which has vertical waste and vent portions 13 and 14, the waste portion 13 being enlarged a short distance above its connection to the fitting 5, and has a waste opening 15^a into the enlargement 15 through 85 which the waste from a basin C may be received. The fitting 12 likewise has in its upper portion a crossover or connection 16 between the waste and vent portions, which is arranged at a height so that in event of 90 stoppage in the lower end of the fitting 12 the waste will overflow into the vent portion 14 only after the waste has backed up and has shown in the bottom of the basin connected through the opening 15^a, thereby indicating a stoppage.

On the succeeding floor level another fitting 5 may be employed, which may be connected to the fitting 12 by ordinary waste and vent sections 17 and 18. The fitting 5 has waste openings 8 for connecting with the waste branches 8^a from various fixtures, such as bath tub and closets.

For a top floor fitting I have shown a fitting 19 with a waste portion 20, and a vent portion 21 which merges into the top of the waste portion 20, which at its upper end is connected with the usual vent pipe 23 to the roof. The soil portion is enlarged slightly 105 above its bottom connection to the fitting 5

and receives in such enlarged portion 22 the waste from a fixture such as a wash basin C, as shown. Also, the connection between the vent and stack portions is such a height 5 as to ensure the showing of waste in the basin C in case of a stoppage below the point of entry of the basin waste and above the crossover connection in the uppermost fitting 5.

10 The enlargements 9, 15 and 22, respectively, of the fittings 5, 12 and 19 preferably have parallel walls which extend upwardly substantially without interruption to a constriction in the region of the hub, and because of the enlarged area I have found it is not necessary to protect the entrance of the waste openings into the stack with any mechanical deflecting means.

15 It will therefore be seen that all of the lateral branches enter the fittings at points where the waste portions of the fittings are enlarged, thereby minimizing the possibility of self-siphonage of the fixtures connected with such branches, and also that in the event 20 of stoppage at or below the point of entry of the fixtures into such waste portions the crossovers are so located that the stoppage will cause the waste to back up into such fixtures and by showing therein will indicate 25 that there is a stoppage. It will also be seen that the crossover connections provide adequate venting for the soil and waste branches of the fittings and thereby normally eliminate the necessity of separate vent connections 30 with the fixtures.

35 In Fig. 9 I have shown a modification of a top floor fitting and in Fig. 10 a modification of a lower floor fitting. Both of these fittings have vent openings 25 which are 40 provided to receive vent connections from fixtures which because they are attached upon waste branches of unusual length may require separate vents. These fittings also have two crossover connections 26 and 27 45 for the purpose of providing the maximum air circulation between vent and waste pipes. The enlargement 28 in Fig. 10 is constricted at 29 to prevent the descending column of waste from spreading out and atomizing and thereby causing siphonic action or back 50 pressure.

55 The terms and expressions which I have employed are used as terms of description and not of limitation, and I have no intention, in the use of such terms and expressions, of excluding any mechanical equivalents of the features shown and described, or portions thereof, but recognize that va-

rious structural modifications are possible within the scope of the invention claimed. 60

What I claim is:

1. In a plumbing system, a plurality of vertically extending fittings comprising sections of waste and vent stacks, at least one of the waste sections having an enlargement 65 substantially equal in cross section to the combined normal cross sectional area of the waste and vent stacks, the enlargement having openings for waste from fixtures and extending upwardly undiminished in size to 70 a connection with the vent stack.

2. In a plumbing system, a plurality of vertically extending fittings comprising sections of waste and vent stacks, said waste stack having openings for fixture waste 75 branches leading thereto, an air connection between the two stacks, and an enlargement in a waste section substantially equal in cross section to the combined normal cross 80 sectional area of the waste and vent stacks, the said enlargement extending from below said openings to the air connection between said stacks.

3. In a plumbing system, a plurality of vertically extending fittings comprising integral sections of waste and vent stacks, at 85 least one of the waste sections having openings for waste from fixtures, a passage communicating with the vent stack, and an enlargement extending from below said openings upwardly to the said passage.

4. In a plumbing system, a plurality of vertically extending fittings comprising integral sections of waste and vent stacks of substantially the same diameter, at least one 95 of said waste sections having an enlargement substantially equal in cross section to the combined normal cross sectional area of the waste and vent stacks, said enlargement having waste openings for the discharge 100 from fixtures and a passage communicating with said vent section.

5. In a plumbing system, a plurality of vertically extending fittings comprising integral sections each of which forms a portion 105 of a waste stack and a portion of a vent stack, and contains an air connection between such stack, the waste portion having waste openings leading thereto from fixtures, the said air connection being at a 110 height between the tops and the bottoms of the fixtures connected through said openings to indicate by a showing of waste therein in a stoppage in the waste stack, while preventing the overflowing of said fixtures.

HENRY J. LUFF.
